Primary Examiner — Rhea Shields(74) *Attorney, Agent, or Firm* — Laurence A. Greenberg; Werner H. Stemmer; Ralph E. Locher**CLAIM**

The ornamental design for an electric power controller, as shown and described.

DESCRIPTION

FIG. 1 is a front perspective view of the electric power controller showing my new invention;

FIG. 2 is a front elevation view thereof;

FIG. 3 is a rear elevation view thereof;

FIG. 4 is a top plan view thereof;

FIG. 5 is a bottom plan view thereof;

FIG. 6 is a right side elevation view thereof;

FIG. 7 is a left side elevation view thereof; and,

FIG. 8 is a rear perspective view thereof.

In the drawings, the broken lines are for the purpose of illustrating environment only and form no part of the claimed design.
